[57] **CLAIM**

The ornamental design for an electrical connector casing, as shown and described.

DESCRIPTION

FIG. 1 is a front view of an electrical connector casing showing my new design, the rear view being identical; FIG. 2 is a side view thereof, the opposite side view thereof being identical;

FIG. 3 is a top view thereof;

FIG. 4 is a bottom view thereof;

FIG. 5 is an elevational view of the interior of one of two halves of the casing, the second half, the interior of which is a mirror image of that shown, is omitted for purposes of disclosure;

FIG. 6 is a bottom view of the half as shown in FIG. 5;

FIG. 7 is a longitudinal section thereof, on an enlarged scale, taken along the line 7-7 in FIG. 5, the corresponding view of the other half being identical;

FIG. 8 is a longitudinal section thereof, on an enlarged scale, taken along the line 8-8 in FIG. 5, the corresponding sectional view of the other half being identical.
